(57) **CLAIM**

The ornamental design for a barbecue with hood, as shown and described.

DESCRIPTION

FIG. 1 is a top front isometric view of a barbecue with hood, showing the design;

FIG. 2 is a bottom rear isometric view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The shading lines shown in the drawings represent the three-dimensional contour of the claimed design and are not intended to indicate surface decoration. The dashed lines shown in the drawings illustrate portions of the barbecue with hood that form no part of the claimed design.
